DESIGN FOR A JUVENILE CAR

Rudolph A. Klatt, Tonawanda, N. Y., assignor to Auto-Wheel Coaster Company, Inc., North Tonawanda, N. Y.

Application March 31, 1938, Serial No. 76,211

Term of patent 7 years

To all whom it may concern:

Be it known that I, Rudolph A. Klatt, a citizen of the United States, residing at Tonawanda, in the county of Erie and State of New York, have invented a new, original, and ornamental Design for a Juvenile Car, of which the following is a specification, reference being had to the accompanying drawing, forming part thereof.

In this drawing the figure is a perspective view of the juvenile car showing my new design.

I claim:—

The ornamental design for a juvenile car, as shown.

RUDOLPH A. KLATT.
